Primary Examiner — John Windmuller*Assistant Examiner* — John R Yeh(57) **CLAIM**

The ornamental design for a controller for head-mounted display, as shown and described.

DESCRIPTION

FIG. 1 is a front, top and right side perspective view of a controller for head-mounted display showing our new design; FIG. 2 is a rear, bottom and left side perspective view thereof; FIG. 3 is a front view thereof; FIG. 4 is a rear view thereof; FIG. 5 is a left side view thereof; FIG. 6 is a right side view thereof; FIG. 7 is a top plan view thereof; and, FIG. 8 is a bottom plan view thereof. The broken lines in the figures represent features of the device which form no part of the claimed design.

1 Claim, 6 Drawing Sheets(56)
